UNITED STATES PATENT OFFICE.

GEORGE B. COMPTON, OF ST. LOUIS, MISSOURI.

DUMMY ADVERTISING-PACKAGE.

979,261.

Specification of Letters Patent. Patented Dec. 20, 1910.

Application filed April 29, 1910. Serial No. 558,420.

To all whom it may concern:

Be it known that I, GEORGE B. COMPTON, a citizen of the United States of America, residing in the city of St. Louis and State 5 of Missouri, have invented certain new and useful Improvements in Dummy Advertising-Packages, of which the following is a full, clear, and exact description, reference being had to the accompanying drawings, 10 forming part of this specification.

My invention relates to a dummy paper package of the character commonly displayed in store windows to advertise various commodities contained in smaller packages 15 of like kind. These advertising packages are usually imitations of the small package on a very large scale and are not intended to be used as containers.

The object of my invention is to produce 20 a substantial cylindrical knock-down dummy package of this character having very simple parts which can be very easily interlocked with each other.

Figure I is a perspective view of a cylindrical dummy paper package embodying the features of my invention. Fig. II is a perspective view showing parts of the dummy package ready to be assembled. Fig. III is a section taken on line III—III, Fig. I. Fig. 30 IV is a section taken on line IV—IV, Fig. I.

In the accompanying drawings: A designates a cylindrical body made of a sheet of paper, the edges of which overlap when the body of the dummy package is formed, one 35 of the edges of the sheet being provided with pairs of parallel slits 1 and 2 adapted to receive locking tongues 3 which project from the other edge. Each tongue 3 passes through a pair of the slits 1 and 2 (see Fig. 40 IV), extends into the package and has its free end interposed between the overlapping portions of the sheet A. These tongues can be very easily folded backwardly to pass through the slits as just described, and when 45 so arranged they are very firmly held in position by the overlapping portions of the sheet which frictionally engage and interlock with the ends of the tongue, thus completing the body of the dummy package. 50 The body A is provided near its ends with pairs of parallel slits 4 which produce yielding webs 5 having their ends integrally connected to the body A.

B designates the heads of the package which are formed of a single sheet of paper 55 and are of a circular shape. At intervals around the edge of each head are tongues 6 bent at a right-angle to the plane of the head. The heads B are inserted into the cylindrical body A at its ends, and the 60 tongues 6 of these heads are, for the purpose of securing the heads to the body A, passed through the outermost slit 4, and then through the innermost companion slit 4, it being understood that to permit such 65 passage of the tongues, the webs 5 are bent inwardly, as illustrated in the drawings. These inwardly bent webs form stops adapted to engage the heads B and limit inward movement thereof. As seen in Fig. 3, the 70 tongues 6, upon being introduced as has been stated, are caused to bear at their outer faces against the wall of the body A above and beneath the webs 5, and at their inner faces against said webs, whereby they are 75 held in position within the body with a sufficient degree of firmness to prevent the escape of the heads from the body of a dummy package, and such dummy package is therefore made adequately substantial for the use 80 for which it is intended, namely, that of serving as an advertising medium, in which connection it is not necessary to place any contents in the package.

I claim:

A dummy paper package comprising a cylindrical body made of a sheet of paper having pairs of slits adjacent its ends and inwardly bent webs between said slits, and means for holding the edges of said sheet 90 of paper together, said means including a pair of circular paper heads inserted into opposite ends of the cylindrical body, the inwardly bent webs forming stops adapted 95 to engage said heads, each of said heads having a circular row of tongues which extend toward the middle of the body, pass through said pairs of slits, and bear at their free ends against the interior of the body and at their inner ends against the exterior of said webs

GEO. B. COMPTON.

In the presence of—

E. B. LINN,
A. J. McCauley.
